(57) **CLAIM**

The ornamental design for a detachable door securement device, as shown and described.

DESCRIPTION

FIG. 1 is a top, front, right perspective view of a detachable door securement device, according to the design.

FIG. 2 is a front view of the detachable door securement device, according to the design.

FIG. 3 is a rear view of the detachable door securement device, according to the design.

FIG. 4 is a left side view of the detachable door securement device, according to the design.

FIG. 5 is a right side view of the detachable door securement device, according to the design.

FIG. 6 is a top view of the detachable door securement device, according to the design.

FIG. 7 is a bottom view of the detachable door securement device, according to the design; and,

FIG. 8 is a top, front, right perspective view of the detachable door securement device, in a door and door frame environment, according to the design.

The dot-dash-dot broken lines are included for the purpose of illustrating environmental structure and form no part of the claimed design.

1 Claim, 8 Drawing Sheets
